DESIGN FOR A COIN CHANGING MACHINE

Jerome E. Hagstrom, Kansas City, Mo., assignor
to C. Earl Hovey, Kansas City, Mo., trustee

Application August 16, 1940, Serial No. 94,469

Term of patent 14 years

To all whom it may concern:

Be it known that I, Jerome E. Hagstrom, a citizen of the United States, residing at Kansas City, in the county of Jackson and State of Missouri, have invented a new, original, and ornamental Design for a Coin Changing Machine, of which the following is a specification, reference being had to the accompanying drawing, forming a part thereof.

Fig. 1 is a front elevational view of the coin changing machine, showing my design.

Fig. 2 is an edge view thereof; and

Fig. 3 is a top plan view thereof.

I claim:

The ornamental design for a coin changing machine, as shown.

JEROME E. HAGSTROM.
